(57) **CLAIM**

The ornamental design for a pet side table as shown and described.

DESCRIPTION

FIG. 1 is a top front left perspective view of a pet side table according to a first embodiment showing our new design; FIG. 2 is a front elevational view of the pet side table according to the first embodiment;

FIG. 3 is a rear elevational view of the pet side table according to the first embodiment;

FIG. 4 is a left side view of the pet side table according to a first embodiment;

FIG. 5 is a right side view of the pet side table according to the first embodiment;

FIG. 6 is a top plan view of the pet side table according to a first embodiment;

FIG. 7 is a bottom plan view of the pet side table according to the first embodiment;

FIG. 8 is a top front left perspective view of a pet side table according to a second embodiment showing our new design; FIG. 9 is a front elevational view of the pet side table according to the second embodiment;

FIG. 10 is a rear elevational view of the pet side table according to the second embodiment;

FIG. 11 is a left side view of the pet side table according to the second embodiment;

FIG. 12 is a right side view of the pet side table according to the second embodiment;

FIG. 13 is a top plan view of the pet side table according to the second embodiment; and,

FIG. 14 is a bottom plan view of the pet side table according to the second embodiment.

The broken lines in the drawings are for the purpose of illustrating portions of the article that form no part of the claimed design.
